UNITED STATES PATENT OFFICE.

PERCE W. MILLER, OF MCKEESPORT, PENNSYLVANIA.

METAL-BENDING MACHINE.

1,322,926.

Specification of Letters Patent. Patented Nov. 25, 1919.

Application filed November 23, 1916. Serial No. 133,028.

To all whom it may concern:

Be it known that I, PERCE W. MILLER, a citizen of the United States, residing at McKeesport, in the county of Allegheny 5 and State of Pennsylvania, have invented certain useful Improvements in Metal-Bending Machines, of which the following is a specification, reference being had therein to the accompanying drawing.

10 The invention relates to a bending machine, and more particularly to the class of sheet metal bending machines.

The primary object of the invention is the provision of a machine of this character 15 wherein sheet metal in strip form, when fed therein, will be automatically bent and shaped into a tube, pipe or the like, and the seam of the strip will be overlapped for the welding of the joint when the tube, pipe or 20 the like has been delivered from the machine.

Another object of the invention is the provision of a machine of this character wherein the forming rolls are of novel construction and are arranged in successive order 25 for the complete bending of the material into tube or pipe form when fed thereinto and prior to the delivery of the same from the machine, so that the welding operation 30 is only necessary on the delivery of the tube or pipe from said machine.

A further object of the invention is the provision of a machine of this character wherein the cores or dies and the shaping 35 elements are of novel form and positioned in a novel manner within the machine so as to assure the successful bending of the strip material into tubi-form with accuracy and without any irregularity in the shaping 40 thereof.

A still further object of the invention is the provision of a machine of this character wherein the forming rolls are mounted for adjustment so as to accommodate various 45 thicknesses of strip material and to properly bend the strip material when fed through the machine, the shaping of the material into tubi-form being effected in a single operation of the machine for the subsequent 50 welding process after the shaping of the material.

A further object of the invention is the provision of a machine of this character which is simple in construction, thoroughly

reliable and efficient in operation, and inexpensive in manufacture and installation.

Other objects will be in part obvious and in part hereinafter set forth.

The invention accordingly consists in the features of construction, combination of elements and arrangement of parts which will be exemplified in the construction herein-after described, and the scope of the application of which will be indicated in the appended claims.

65 In the accompanying drawings:

Figure 1 is a side elevation of a machine constructed in accordance with the invention;

Fig. 2 is a top plan view thereof; 70

Fig. 3 is an elevation of a pair of the forming rolls at the feed end of the machine;

Fig. 4 is a similar view of another pair 75 of the forming rolls;

Fig. 5 is a similar view of another pair of the forming rolls at the delivery end of the machine;

Fig. 6 is an end elevation of the blank 80 sheet material when fed to the machine;

Fig. 7 is an end elevation of said sheet material showing the shape thereof in the initial bending;

Fig. 8 is an end elevation showing a further step in the bending of the material; 85

Fig. 9 is an end elevation of the final step in the bending of the material;

Fig. 10 is a perspective view of the guide feed trough and the guard members separated; 90

Fig. 11 is a perspective view of one of the dies or cores;

Fig. 12 is a perspective view of the forming trough cooperative with the die shown in Fig. 11; 95

Fig. 13 is a vertical transverse sectional view through the trough and die shown in Figs. 11 and 12;

Fig. 14 is a perspective view of another forming guide; 100

Fig. 15 is a perspective view of the die or core for the guide shown in Fig. 14;

Fig. 16 is a vertical transverse sectional view through the die or core shown in Fig. 15. 105

Similar reference characters indicate corresponding parts throughout the several views of the drawings.

Referring to the drawings in detail, A designates a base which may be of any desirable shape and length and is supported upon a foundation or flooring, while rising at intervals from said base are sets of bearing frames B, C and D, respectively, the latter being located at the delivery end of the machine, while the frames B are at the feed end and the frame C at an intermediate point, as clearly shown in Figs. 1 and 2 of the drawings. The frames B each includes a pair of vertical uprights 10 which are formed with suitable guideways in which are slidably fitted upper and lower cross bearings 11 and 12 respectively which are adjustable relative to each other through the medium of adjusting screws 13 carrying lock nuts 14 threaded thereon, and working against the cross bearings 12 at opposite sides thereof so that the bearings will be held in their adjusted position. Journaled in the bearings 11 and 12 are the shafts 15 of initial upper and lower bending rolls 16 and 17 respectively, the same being located centrally between the frames B. The roll 16 is formed with a convexed periphery 18, while the roll 17 is formed with a concaved periphery 19 so as to form companion rolls in the initial bending of the strip material 20, which is normally flat and of the required length. On the adjustment of the cross bearings 11 and 12 the rolls 16 and 17 can be positioned relative to each other for the proper matching of the peripheries thereof in the initial bending of the sheet material 20 when fed therebetween.

At the feed end of the machine and suitably supported between the bearing frames 10 is a feed trough 21 for the sheet material 20, and this trough is formed with a tapered end 22 next to the rolls 16 and 17 having a tip 23 shaped correspondingly to the concaved periphery 19 of the roll 17 so as to properly feed the sheet material 20 from the trough 21 which is formed with the side upstanding flanges 24 which terminate at the point of juncture of the extension 22 with said trough. Adjustably mounted upon the bearing frames 10 are the guide members, each comprising a base 25 having an elongated slot 26 for the adjustable fastening of the same to the frame 10 and an arm 27 forming a guard, the said arms of both shaping members being disposed in convergent relation and projecting in the direction of the trough 24 to be disposed in the position shown in Fig. 2 of the drawing so that the sheet material 20 advanced in the trough will be guided between the guard arms 27 for the initial shaping thereof into substantially U-form, by the initial forming rolls 16 and 17, as at 28 in Fig. 7, at the feed end of the machine. The guide members at the feed end of the machine can be adjusted laterally toward and away from each other

for the proper positioning thereof according to the thickness of the strip material 20 advanced in the trough 21 into the machine.

The frames C each comprises inner and outer vertical uprights 29 and 30, respectively, which have suitable guideways formed therein for the slideable mounting of cross bearings 31 adjustable under the action of inner and outer pairs of adjusting screws 32 and 33 respectively, and on these bearings 30 and 31 in boxings 34 are journaled the shafts 35 which are angularly disposed in upwardly convergent relation to each other and carry at their inner ends meshing gears 36 so that motion from one shaft will be imparted to the other shaft, while one of these shafts carries a driving belt wheel 37 over which is trained a belt 38 operated from a motor 39 preferably of the electric type and supported at the base A of the machine. The shafts 35 have thereon the companion forming rolls 40, each provided with the single flanged periphery 41 and the pair of rolls act upon the strip material to bend the same into the shape, as at 60, shown in Fig. 8 of the drawings.

Located between the rolls 16 and 17 and the rolls 40 is a guide trough 42 which, at one end, is formed with the tube portion 43, while at opposite extremities of said trough are the tips 44 and 45, respectively, which match the forming rolls 16, 17 and 40, said trough 42 being supported between the frames B and C in any suitable manner, and co-operating with the trough 42 is the die or shaper 46 which is adjustably supported through the medium of screws 47 and is of the formation shown in Fig. 11 of the drawings, with the end 48 adapted to enter the tube end 43 of said trough 42 for the initial shaping of the strip material 20 prior to action of the forming rolls 40 thereon to bend the strip into the shape shown in Fig. 8 of the drawings.

At the delivery end of the machine are the final forming rolls 49 and 50 respectively, the latter being formed with a concaved periphery 51 while the roll 49 is formed with the concaved lapped peripheral portions 52 and 53, respectively, for action upon the strip to finally shape the same as at 54 in Fig. 9 of the drawings on the delivery thereof from the machine, the rolls 49 and 50 being adjustably supported by the frames D in a manner similar to the supporting of the rolls 16 and 17 in the frames B at the feed end of the machine.

Located between the frames C and D is the tubular shaper 55 formed with the tips 56 as shown in Fig. 14 of the drawings, and this shaper is adjustably supported through the medium of adjusting screws 57, while within the shaper 55 is a core or mandrel 58 shown in Figs. 15 and 16 of the draw-

ings, the core or mandrel being provided longitudinally thereof with a lapped shoulder 59 which accommodates the lap joint of the strip 54 initially before final action 5 thereon by the rolls 49 and 50 which close the overlapped edges of the strip 54 at the joint for the subsequent welding of said edges in the welding process to complete the tube or pipe.

10 The shafts of the forming rolls 16 and 17 and 49 and 50 carry belt pulleys 61 over which are trained the belts 62 which are driven from motors 63 preferably of the electric type.

15 In the operation of the machine, the sheet strip 20 is bent from its flat formation into tubi-form or pipe shape from the feed end to the delivery end of the machine, with the overlapped seam which is welded 20 in the welding process after the delivery of the completed tube or pipe from said machine.

25 The core or mandrel 58 is supported at any suitable point from the machine so as to be positioned within the shaper 55 for the final feed of the strip material to the forming rolls 49 and 50 and the subsequent delivery of the completed tube or pipe from the machine. The frames C are adjusted laterally 30 on guides 64 upon the base A so as to properly position the forming rolls 40 in their companion relationship to each other.

35 From the foregoing description, taken in connection with the accompanying drawings, the construction and operation of the here-

in described metal bending machine will be readily apparent and, therefore, a more extended explanation has been omitted.

Having thus described my invention, I claim:

1. In a tube bending machine, a guide trough provided with opposite tip extremities, pairs of forming rolls arranged at the extremities of said trough, the tip extremities of said trough being shaped to match 40 correspondingly the forming peripheries of said rolls, a tubular portion adjacent one extremity to assist in the formation of a metal blank subsequent to the action of one pair of rolls and prior to the action of the 45 other pair of rolls thereon, and a die or shaper overhanging the trough and coöperating therewith.

2. In a tube bending machine, a guide trough provided with opposite tip extremities, pairs of forming rolls arranged at the extremities of said trough, the tip extremities of said trough being shaped to match 55 correspondingly the forming peripheries of said rolls, a tubular portion formed on said 60 trough adjacent one extremity to assist in the formation of a metal blank subsequent to the action of one pair of rolls and prior to the action of the other pair of rolls thereon, a die or shaper overhanging the trough 65 and coöperating with the same and the tubular portion, and means for adjusting the die or shaper relative to the trough.

In testimony whereof I affix my signature.

PERCE W. MILLER.
